CLAIM

The ornamental design for a brush, as shown and described.

DESCRIPTION

FIG. 1 is a front elevation view

FIG. 2 is a rear elevation view

FIG. 3 is a left side elevation view

FIG. 4 is a right side elevation view

FIG. 5 is a top plan view,

FIG. 6 is a bottom plan view; and,

FIG. 7 is an enlarged view of portion "7" shown in FIG. 1. The broken lines shown in the drawings show portions of the article and form no part of the claimed design. The dot-dash broken lines shown in FIGS. 1 and 7 are enlarged view indicators, and form no part of the claimed design.

1 Claim, 4 Drawing Sheets
